POWER NAIL FILE, OR SIMILAR ARTICLE

Herbert B. Baron, St. Charles, Ill., assignor to Industrial Design Engineering and Sales, Chicago, Ill., a corporation of Illinois

Filed Oct. 15, 1965, Ser. No. 87,508

Term of patent 3½ years

(Cl. D86—10)

FIG. 1 is a side elevational view of a power nail file showing my new design.

FIG. 2 is an end view as seen from the right of FIG. 1.

FIG. 3 is a top plan view.

FIG. 4 is an end view as seen from the left of FIG. 1.

FIG. 5 is a bottom plan view.

The broken line showing of the nail file in FIGS. 1, 3 and 5 is for illustrative purposes only. The essential features of the design reside in the full lines shown on the drawing.

I claim:

The ornamental design for a power nail file, or similar article, as shown and described.
